UNITED STATES PATENT OFFICE.

JOSEPH F. DELCOURT, OF NEW BEDFORD, MASSACHUSETTS.

CLASP.

1,382,484.

Specification of Letters Patent. Patented June 21, 1921.

Application filed January 20, 1921. Serial No. 438,684.

To all whom it may concern:

Be it known that I, JOSEPH F. DELCOURT, a citizen of the United States, residing at New Bedford, in the county of Bristol and 5 State of Massachusetts, have invented certain new and useful Improvements in Clasps; and I do declare the following to be a full, clear, and exact description of the invention, such as will enable others skilled 10 in the art to which it appertains to make and use the same.

This invention relates to an improved clasp of the type disclosed in my prior application, filed August 20, 1920, Serial No. 15 404,893, and is an improvement over the structure shown therein. One object of the invention is to so construct the clasp that a strip of fabric similar to a garter strap may be connected with the lower jaw of the clasp 20 in an improved manner, one portion of the garter strap being stitched to the lower jaw and the end portion of the strap being passed about the lower end of the jaw and through a transversely extending slot formed therein, 25 so that the end of the strap will be positioned between the lower jaw and the portion of the strap beneath the jaw.

Another object of the invention is to so construct the upper jaw that if desired, the 30 garter strap may be connected with a loop carried by the upper jaw and positioned about a resilient arm carried by the lower jaw.

Another object of the invention is to so 35 construct the lower jaw that the goods engaged by the two jaws may be forced into side pockets formed in the lower jaw and thus the goods prevented from slipping longitudinally between the two jaws.

40 Another object of the invention is to so construct the actuating lever for the movable jaw that its end portion may be easily engaged by the finger when it is desired to swing the lever upwardly to move the jaws 45 to a releasing position.

Another object of the invention is to so 50 construct this clasp that the resilient arm will have a great deal of resiliency and the actuating lever securely held in a lowered position, latching means being provided to releasably hold the lever in a lowered position.

55 Another object of the invention is to so construct the clasp that the portion of the article clamped between the two jaws may

be held flat and securely clamped between the jaws.

This invention is illustrated in the accompanying drawings, wherein:

Figure 1 is a perspective view of the improved clasp. 60

Fig. 2 is a view showing the improved clasp in an open position and shown partially in side elevation and partially in vertical section. 65

Fig. 3 is a view similar to Fig. 2 showing the clasp in the closed position.

Fig. 4 is a vertical transverse sectional view taken along the line 4—4 of Fig. 3.

Fig. 5 is a view in side elevation showing 70 a modified construction of clasp.

Fig. 6 is a top plan view of the clasp shown in Fig. 5.

This improved clasp is somewhat similar 75 in construction to that disclosed in my prior application, and is provided with a lower jaw 1 and an upper jaw 2, the upper jaw being formed of separate side plates which have their outer edge portions bent down to provide depending flanges 3 and have their 80 inner side portions bent upwardly and riveted together to provide a longitudinally extending rib 4, the rib 4 being cut to provide a circular opening 5 to receive a circular disk 6. The strip of sheet metal from 85 which the lower jaw 1 is formed is resilient and has one end portion bent upwardly and split longitudinally to provide arms 7, the end portions of which are rolled to provide 90 bearings 8 thus providing means for carrying a pivot pin 9. An actuating lever similar to that shown in the prior application has been provided and this lever is provided with a head 10 and side arms 11 which extend upon opposite sides of the rib 4 and 95 between the bearings 8. The disk 6 which is positioned in the circular opening 5 is connected with the side arms 11 by means of a rivet or pin 12 which is positioned to one side of the center of the disk 6. The 100 disk 6 is further provided at its periphery and diametrically opposite the pin 12 with an opening registering with openings formed in the arms 11 to receive the pivot pin 9. It will thus be seen that the lever and the 105 disk 6 will turn upon this pivot pin 9, the disk 6 providing an eccentric for swinging the jaw 2 into and out of contact with the jaw 1 and longitudinally thereof when in engagement with the lower jaw. It will be 110

further noted that the head 10 of this lever extends forwardly beyond the side arms 11 and has its end portion cut to provide a notch 13 so that when the lever is swung 5 down to the position of Fig. 3 and it is desired to raise the lever, this head may be engaged with a thumb nail fitting into the notch 13. Therefore, the lever can be very easily swung upwardly to a releasing position. In order to permit the lever to be locked in the lowered position, one of the rivets which connects the inner side portions of the upper jaw to provide the rib 4, has been extended thus providing a stud 14 which will fit into a socket 15 formed in one of the side arms 11 of the lever. This stud slides into and out of the pocket 15 and will serve to releasably hold the lever in the lowered position but permit of it being 20 freely moved to a raised position when desired. In order to permit the garter strap 16 to be connected with the lower jaw 1, this lower jaw has been provided adjacent its upper end with thread receiving openings 17 and adjacent its lower end with a transversely extending slot 18. The strap 16 is placed beneath the jaw 1 and has its lower free end carried upwardly over the lower end of the jaw and then passed down 25 through the slot 18 to extend upwardly against the under face of this jaw. The strap is then secured by means of stitches 19 which pass through the openings 17 and the strap will be securely held in place.

30 In the form shown in Figs. 5 and 6, the structure is in general similar to that shown in Fig. 1 through 4 and in general it is not necessary to specifically describe the parts, similar reference numerals in these figures 35 referring to similar parts in the forms disclosed in Fig. 1 through 4. It should be noted however that in this form, the openings 17 and the slot 18 have been done away with and instead of having the garter strip 16 connected with the lower jaw 1, this 40 garter strip will be formed into a loop which will pass through an enlarged eye 20 which extends rearwardly from the upper jaw and extends about the resilient arm carried by 45 the lower jaw. It should be further noted that in this form, the lower jaw 1 has its side portions cut to provide notches or recesses 21 so that when the clasp is in use, the strip of material which is clamped between the two jaws will be forced into these 50 side notches by the depending flanges 3 of the upper jaw and thus the strip of material firmly held between the two jaws. It will thus be seen that there has been provided a clasp construction in which the strip 16 may be connected with the lower jaw 1 or if so desired, a modified form may be used in which the strip 16 may be connected

with the upper jaw. It will be further noted that there has been provided a clasp which will be very efficient in operation and which may be easily moved to an open or closed position and which will securely engage the fabric between the jaws and the jaws securely but releasably held in a closed 70 or clamping position. 75

I claim:

1. A clasp comprising a jaw, an overhanging arm carried thereby, a second jaw between the first jaw and arm thereof, a rib carried by the second jaw, and an actuating lever having a head and side arms extending upon opposite sides of said rib, the arms having connection with the rib and the rib having a latching stud extending from one side for fitting into a socket formed in one of the side arms of said lever and the lever head extending beyond the jaws and having its end portion notched to provide a finger nail securing seat. 80

2. A clasp comprising a flat jaw provided with side notches, a support carried by said jaw, a second jaw between said support and first jaw and provided with depending side flanges, and actuating means movably carried by the support and having connection with said second jaw. 90

3. A clasp comprising a jaw, a support carried thereby and in overhanging relation to the jaw, a second jaw between said support and first jaw, a relatively large hanger engaging eye carried by the second jaw with said support extending through the eye and the eye extending longitudinally of the jaws, and actuating means pivotally carried by said support and having eccentric connection with the second jaw for moving one jaw toward and away from the other and then longitudinally thereof with the support moving longitudinally in the eye. 100

4. A clasp comprising a jaw, a support carried thereby and in overhanging relation to the jaw, a second jaw between said support and first jaw, the first jaw having openings for receiving fastener means engaging a carrier strip beneath the jaw and the jaw at its forward end having a transversely extending slot for receiving the end of the carrier strip carried upwardly over the end of the jaw and passed down through the slot, and actuating means carried by said support and having connection with the second jaw. 110

5. The structure of claim 7 having the second jaw movable longitudinally of the first jaw and when moved to a clamping position moving inwardly beyond the transversely extending slot. 115

In testimony whereof I have hereunto set my hand.

JOSEPH F. DELCOURT.
